UNITED STATES PATENT OFFICE.

ROBERT D. JEFFREYS, OF NEWBURGH, NEW YORK.

SEPARATOR.

No. 837,623.

Specification of Letters Patent.

Patented Dec. 4, 1906.

Application filed June 5, 1906. Serial No. 320,232.

To all whom it may concern:

Be it known that I, ROBERT D. JEFFREYS, a citizen of the United States, residing in Newburgh, county of Orange, and State of New York, have invented a certain new and useful Improvement in Steam-Drying Separators, of which the following is a specification.

This invention has relation to an improvement in that type of devices for drying steam as it leaves the boiler wherein a group of parallel wire screens is interposed in the path of the steam to catch the entrained water.

In devices of this character difficulty has been hitherto met in taking the plates apart for purposes of cleaning and replacing or repairing the plates.

The present invention covers improved means for the suspension, support, and security of devices of this character by the use of which the operation of removing the plates is greatly facilitated.

The invention is illustrated in a preferred form in the accompanying drawings, where-

25 in—
Figure 1 is a side elevation of my device as fastened at the top of a boiler. Fig. 2 is a cross-section of the same. Fig. 3 is a perspective view of the withdrawing-tool for the compression-head. Fig. 4 is an elevation of the compression-head. Fig. 5 is a cross-section of the same on the plane α α in Fig. 4. Fig. 6 is a longitudinal section of the suspension-bar, and Fig. 7 is an end elevation of the same.

35 The device is adapted for suspension at the top of a boiler, a portion of which is shown at 1 in Figs. 1 and 2. The main steam-pipe is shown at 2, and the terminal steam-chamber 40 3 of the separator is located directly beneath the steam-pipe 2, being connected thereto by an adjustable connecting-pipe 4 in a well-known manner.

In devices of this type the steam-chamber 45 3 is sometimes located at one end of the group of separator-plates and is sometimes placed between two groups of such plates. Both forms being well known in the art, it is not necessary to illustrate more than one form; 50 but it is to be understood that my invention is applicable to either form.

In the form shown one end of the separator is supported by a strap 5, firmly secured to the boiler by the bolt 6 in a well-known 55 manner, while the opposite end of the separa-

tor is provided with a novel form of suspension, hereinafter described and claimed.

In separators of this type the wire screens 7 are placed parallel side by side between spacing plates or frames 8, the whole being 60 strung upon two parallel supporting-rods 9 and 10 and being compressed together by nuts 11 on said rods bearing upon the sides of a compression-head 12.

In prior forms of separator of this type it 65 has been necessary to remove the compression-head at one end and to slip the spacing-plates and screens off of the rods 9 10 in order to get at the screens and plates to clean them or for repairs. In my improved device here- 70 in described the inconvenience involved by this proceeding is avoided, it being only necessary to move the compression-head a fraction of an inch, so as to loosen the plates and then to pick out and remove whatever plates 75 or screens it is desired to reach without materially disturbing the others. With this end in view the distance plates or frames are constructed as shown in Fig. 2, with simple shoulders symmetrically placed at the oppo- 80 site ends of the frames, the shoulder at one side being longer than that on the other. In the preferred form shown these shoulders take the form of recesses or notches 13 14, so that a double shoulder is afforded at each end, 85 and each frame can be put in either side up at will. In arranging the frames I prefer to place the deep recess 14 in successive plates on opposite sides alternately, so that, as shown in Fig. 2, a deep and a shallow notch 90 succeed each other alternately along the length of each rod 9 and 10.

The compression-head consists of a heavy frame 15, having holes 16 at the ends to receive the rods 9 and 10 and provided with a 95 socket 17, preferably integral with the frame 15, which socket serves the double purpose of receiving the suspending device and of affording a point of engagement for the withdrawing-tool.

The socket 17 is provided with a deep flat chamber 18 and with a depending fork 19, seen from within the separator looking outward in Fig. 4. The back of the fork is cut out to form a squared recess 20 to receive the 105 head of the withdrawing-tool.

The suspension-bar preferably used, as shown at 21 in Figs. 1, 6, and 7, is provided with a tongue 22, adapted to enter the chamber 18, and a depending fork 23, which stands 110

opposite and parallel to the fork 19 of the socket 17.

One end of the bar 21 is fixed by a bolt 24 to the top of the boiler, as shown in Fig. 1, 5 and as the tongue 22 fits into the chamber 18 the horizontal position of the whole device is preserved.

In normal use the various parts of the separator are firmly clamped together by bolts 10 11 and supported as above described. When it is desired to get at any of the plates or screens to remove them for any purpose, the bolts 11 are loosened up, the compression-head 12 is drawn slightly to the right in Fig. 15 1, and any one or more of the plates can be withdrawn without disturbing the others by simply pushing any given plate, so that the bottom of its deep groove is pushed against the corresponding rod 9 or 10, drawing down 20 the opposite end which has thus been freed from its rod and then pulling the plate or frame in the opposite direction off of the remaining rod. To replace the frame, this operation is reversed.

25 For the purpose of conveniently moving the compression-head, as above described, a withdrawing-tool is used, composed, preferably, of a T-shaped bolt 25, having a squared head 26, as shown in Figs. 1 and 3. This bolt is simply introduced within the two forks 19 and 23, so that the head 26 occupies the recess 20 in the fork 19, whereupon the nut 27 on one end of the bolt is tightened, so as to draw the two ends of the forks 19 and 35 23 together, and thus cause the head 12 to slide along the rods 9 and 10.

Various changes may be made in this device without departing from my invention, and I do not limit myself to the details herein 40 shown and described.

What I claim is—

1. A steam and water separator comprising longitudinal supports on opposite sides and spacing-frames provided with oppositely-placed shoulders resting on said supports, the shoulder on one side of each frame being deeper than that on the other, substantially as described.

50 2. A steam and water separator comprising longitudinal supports on opposite sides and spacing-frames provided with oppositely-placed shoulders resting on said supports, the shoulder on one side of each frame being

deeper than that on the other and said frames being arranged with the deep shoulder of 55 each next the shallow shoulder of the next, substantially as described.

3. A steam and water separator comprising longitudinal side supporting-rods, spacing-plates having deep and shallow notches 60 on opposite sides embracing said rods, compression-heads strung on said rods and means for compressing said frames between said heads, substantially as described.

4. A steam and water separator comprising 65 parallel spacing-frames suspended together, a virtually-horizontal suspension-bar and a compression-head for said frames sliding upon and supported by said bar, substantially as described.

70 5. In a device of the class described, a virtually-horizontal suspension-bar, a compression-head supported thereby and capable of sliding thereon and means connected with said bar for drawing the compression-head 75 along the same, substantially as described.

6. In a device of the class described, a compression-head having a socket, a suspension-bar fitting into said socket and means connected with said bar and socket for drawing 80 the compression-head along the suspension-bar substantially as described.

7. In a device of the class described, a compression-head, a socket therein provided with a fork, a suspension-bar, fitting into said 85 socket and also provided with a fork and a T-shaped bolt adapted to enter both of said forks for drawing the compression-head along the suspension-bar, substantially as described.

8. As an article of manufacture, a spacing 90 means for steam and water separators comprising an open frame turning inward at opposite ends to form a deep and a shallow groove, substantially as described.

9. In a device of the class described, a compression-head having a socket, a suspension-bar fitting into said socket and a removable bolt adapted to engage said bar and socket for drawing the compression-head along said 95 suspension-bar, substantially as described.

ROBERT D. JEFFREYS.
